CLAIM

The ornamental design for a handheld communication device, as shown and described.

DESCRIPTION

FIG. 1 is a front perspective view of a first embodiment of a handheld communication device;

FIG. 2 is a rear perspective view thereof;

FIG. 3 is a front view thereof;

FIG. 4 is a first side view thereof;

FIG. 5 is a second side view thereof;

FIG. 6 is a top view thereof;

FIG. 7 is a bottom view thereof;

FIG. 8 is a front perspective view of a second embodiment of a handheld communication device;

FIG. 9 is a rear perspective view thereof;

FIG. 10 is a front view thereof;

FIG. 11 is a first side view thereof;

FIG. 12 is a second side view thereof;

FIG. 13 is a top view thereof; and,

FIG. 14 is a bottom view thereof.

The broken lines shown in FIGS. 1-14, that are immediately adjacent to the shaded areas, and define the unshaded regions, show portions of the handheld communication device that form no part of the claimed design.
